UNITED STATES PATENT OFFICE.

JOHN CUTHBERT, OF CHICAGO, ILLINOIS, ASSIGNOR TO ECONOMY FUSE AND MANUFACTURING COMPANY, OF CHICAGO, ILLINOIS, A CORPORATION OF NEW YORK.

ELECTRIC FIXTURE.

Application filed May 21, 1920. Serial No. 383,084.

To all whom it may concern:

Be it known that I, JOHN CUTHBERT, a citizen of the United States, residing at Chicago, in the county of Cook and State 5 of Illinois, have invented certain new and useful Improvements in Electric Fixtures, of which the following is a specification.

This invention relates to electric fixtures.

It relates more particularly to fixtures 10 comprising electric sockets and insulating supports.

One of the objects of the invention is to provide an improved electric fixture.

Another object is to provide for the ready 15 application of electric sockets to insulating supports.

Another object is to provide an insulating support to which an electric socket may be readily attached.

20 Another object is to provide an improved socket attaching means for an insulating support.

Other objects and advantages will appear from the specification and claim.

25 An embodiment of the invention is illustrated in the accompanying drawing, wherein:—

Fig. 1 is an elevation of a socket and support.

30 Fig. 2 is a partial sectional elevation of a socket and support, and

Fig. 3 is a longitudinal section of the socket holding eyelet before application to a support.

35 The fixture comprises, in general, an electric socket 5, an insulating supporting base 6 and means for holding the socket and base together.

Socket 5 may be of the general type or-

40 dinarily used for receiving plug lamp sockets, connectors, etc., and may be of any desired size and ornamental design. Examples of sockets which may be satisfactorily used are illustrated in my copending

45 applications Serial No. 383,082; filed May 21, 1920, and Serial No. 383,085; filed May 21, 1920. It is provided with a rounded base end and an exteriorly threaded projection 7, having an opening for passing conductors into the interior. The socket illustrated is a plug receiving lamp socket.

50 Support or base 6 may be of any desired shape, size and construction having a depression 6' to receive the base end of a

55 socket. Ordinarily such supports are com-

posed of porcelain and have openings therethrough for receiving suitable fastening bolts or screws.

The center of the support is depressed to form a seat or nest for the rear of the socket 60 as at 6' and is provided with a hole therethrough. Into this hole is placed an eyelet 8, interiorly threaded to receive projection 7.

The socket and support are assembled by 65 screwing projection 7 into eyelet 8.

Eyelet 8 may be made in the form shown in Fig. 3 when ready to be attached to the support. The eyelet has a flange 9 at one end for overlying the edge of the center opening through the support. The eyelet is inserted in the opening of the support so that the outer surface of flange 9 is flush with the surface of the socket seat and then its opposite end is riveted or spun over the 75 other edge of the hole in the support.

The eyelet may be threaded either before or after it is inserted in and secured to the support. It is preferred to thread the eyelet after application to the support, since, then, the pressure required in the riveting or spinning operation does not tend to destroy the threads.

Providing insulating supports with a depression to receive the base end of the socket 85 and the threaded eyelets and the sockets with threaded projections, as described, sockets and supports may be readily combined to provide an improved fixture in which the end of the socket enters the insulating support, being drawn thereinto by the threaded coupling members. This greatly strengthens the structure and improves its appearance.

Having described my invention what I 95 claim as new and desire to secure by Letters Patent is:—

An electric fixture comprising a base and a socket, a rounded end on the socket and a rounded depression in the base, the two 100 rounded portions having similar contours, an internally threaded nipple extending interiorly from the bottom of the depression and an externally threaded projection on the socket, said nipple and projection 105 cooperating to draw the socket firmly into contact with the base depression.

In testimony whereof I hereunto subscribe my name.

JOHN CUTHBERT.
